OF   D   19,113

JOHN W. FRIES, OF SALEM, NORTH CAROLINA.

DESIGN FOR A WOVEN FABRIC.

Design No. 19,113, dated May 28, 1889.

UNITED STATES PATENT OFFICE.

JOHN W. FRIES, OF SALEM, NORTH CAROLINA.

DESIGN FOR A WOVEN FABRIC.

SPECIFICATION forming part of Design No. 19,113, dated May 28, 1889.

Application filed May 2, 1889. Serial No. 309,370. Term of patent 14 years.

To all whom it may concern:

Be it known that I, JOHN W. FRIES, a citizen of the United States, residing at Salem, in the county of Forsyth and State of North Carolina, have invented a new Design for Woven Fabrics of which the following is a specification.

My invention consists in a novel design for woven fabrics, which design is represented in the accompanying fac-simile; and it consists in a series of cross-lines formed by the weft or filling threads, which lines vary from straight to serpentine in form, as shown, *A* indicating the fabric as a whole, *a* the straight lines, and *b* the wavy or serpentine lines, which, as shown, vary in degree or extent of waviness as they recede from the straight lines.

The design is ordinarily produced in colors, which may be varied at will, or for which a single color may be substituted, the question of color constituting no part of the invention, though adding to the beauty of the finished article.

Having thus described my invention, I claim—

The design for woven fabrics herein shown and described.

In witness whereof I hereunto set my hand in the presence of two witnesses.

JOHN W. FRIES.

Witnesses:

C. T. PFOHL,
BERNARD J. PFOHL.
